UNITED STATES PATENT OFFICE

140,991

DESIGN FOR A MINIATURE ICON PROJECTOR SHRINE

Arthur G. Dannell, Flushing, N. Y., assignor to
The Peace Light Co., New York, N. Y., a firm composed of Harry S. Goodman and Samuel Marcus

Application January 4, 1945, Serial No. 117,246

Term of patent 14 years

(Cl. D29—23)

To all whom it may concern:

Be it known that I, Arthur G. Dannell, a citizen of the United States, residing at Flushing, in the county of Queens and State of New York, have invented a new, original, and ornamental Design for Miniature Icon Projector Shrines, of which the following is a specification, reference being had to the accompanying drawing, forming part thereof.

I claim:

The ornamental design for a miniature icon projector shrine, as shown.

ARTHUR G. DANNELL.
